Attorney

UNITED STATES PATENT OFFICE

CHRISTOPHER CROSSMAN, OF DETROIT, MICHIGAN

DEVICE FOR CHANGING SPRINGS ON LOCOMOTIVES

Application filed January 3, 1931. Serial No. 506,458.

This invention appertains to railroads and more particularly to novel means for forming a section of a railroad track to facilitate the changing and repairing of springs on locomotives.

Heretofore, jacks have been usually provided for the removal of locomotive springs. The use of these jacks is not only a tedious and laborious operation, but also is extremely dangerous to the mechanics.

It is therefore one of the primary objects of my invention to provide novel means for forming a railroad track, whereby a section thereof can be lowered below the usual horizontal rail plane, between a pair of the driver wheels of the locomotive whereby the intermediate drive wheel can be dropped below its normal plane to facilitate the removal of the spring.

Another prime object of my invention is to provide novel means for raising and lowering the rail section without danger or undue difficulty on the part of the operators.

A still further object of my invention is to provide an improved device for changing the springs on locomotives of the above character, which will be durable and efficient in use, one that will be simple and easy to manufacture, and one which can be placed upon the market at a reasonable cost.

With these and other objects in view, the invention consists in the novel construction, arrangement, and formation of parts, as will be hereinafter more specifically described, claimed, and illustrated in the accompanying drawings, in which drawings:—

Figure 1 is a fragmentary side elevation of a track showing my invention incorporated therewith and illustrating the normal position thereof, a fragment of a locomotive being shown on the track in light lines.

Figure 2 is a similar view showing the track section in its lowered position for facilitating the replacing of a spring.

Figure 3 is a transverse section taken on the line 3—3 of Figure 1.

Figure 4 is a detail fragmentary perspective view illustrating the means of connecting the movable track section with the stationary track section, and

Figure 5 is a detail fragmentary perspective view illustrating the actuating means for the movable track section.

Referring to the drawings in detail, where-in similar reference characters designate corresponding parts throughout the several views, the letter A generally indicates a railroad track constructed in accordance with my invention, and B a standard locomotive. As shown, the locomotive B comprises a plurality of driver wheels 10 and supporting springs 11 therefor.

The track A embodying my invention comprises stationary rail sections 15 and 16, arranged in spaced relation and supported by cross ties 17, which ties are also spaced between the ends of the stationary rail sections 15 and 16. The adjacent ends of the stationary rail sections 15 and 16 support movable rail sections 18 and 19, disposed on opposite sides of the track. Suitable bearing supporting members 20 are bolted or otherwise secured to the inner ends of the stationary rail sections 15 and 16 and these bearing members or brackets 20 project beyond the said stationary rail sections and are of a substantially U-shape in cross section, the side flanges of which are provided with bearing openings 21. The outer ends of the movable rail sections 18 and 19 have their faces cut away as at 22 to permit the flanges thereof to be received in the U-shaped supporting members, and a pivot bolt or the like 23 is passed through the openings 21 and through openings 24 formed in the said outer ends of the movable rail sections.

The inner end of the rail section 18 carries a bearing bracket or the like 25, which is bolted or otherwise secured thereto, as at 26. This bracket extends beyond the inner end of the said movable rail section 18 and is of a substantially U-shape in cross section for receiving the inner end of the rail section 19, which has its base flanges cut away as at 27 to snugly fit therein. The U-shaped bearing portion of the bearing bracket 25 is provided with depending pivot ears 27, which rotatably receive the transversely extending shaft 28. This rock shaft extends entirely across the track and is supported by the bear-

ing bracket member 25 on the opposite sides of the track. Keyed or otherwise secured to the shaft 28, as at 29, are the lift legs 30, the lower ends of which are provided with ground engaging rollers 31. The outer end of the rock shaft 28 can be of polygonal shape in cross section for the reception of a suitable operating handle 32.

In operation of my improved device the 10 locomotive is driven onto the track A, with the drive or other wheel directly above the meeting point of the inner ends of the rail sections 18 and 19 and with the adjacent drive wheels on the stationary track sections 15 and 16. The operating crank or handle 32 is now engaged with the rock shaft 28 and this shaft is rocked so as to lower the track sections 18 and 19, to a position, shown in Figure 2 of the drawings. This will allow the 20 drive wheels directly above the movable track sections 18 and 19 to drop, thereby permitting the convenient removal and replacing of the supporting springs 11 therefor.

After the replacement has been made it is 25 merely necessary to again operate the crank 32 in a reverse direction for bringing the lift legs 30 to a vertical position, which will again rock and lift the movable track sections 18 and 19 on their pivots to their normal horizontal plane, after which the locomotive can 30 be driven off the track in the ordinary manner.

It is to be noted, that the lift legs 30 are mounted off center and are provided with flat 35 upper bearing faces 33. When the legs are in their upright supporting position, the flat faces 33 engage the lower faces of the bearing bracket 25 directly at the meeting position of the rails 18 and 19 and thus supports the 40 rails and this point. This relieves strain on the rock shaft 28.

From the foregoing description, it can be seen that I have provided novel means for facilitating the replacing and repairing of the 45 spring of locomotives.

Changes in details may be made without departing from the spirit or the scope of this invention, but:—

What I claim as new is:

50 1. In a device for facilitating the replacing of locomotive springs, pairs of spaced rigid track sections, movable track sections interposed between the rigid track sections, means pivotally connecting the outer ends of the 55 movable track sections to the rigid track sections, a shoe carried by the inner end of one of the movable track sections for receiving the inner ends of the other movable track sections, and means carried by the shoe for raising and lowering the movable track sections.

55 2. A device for facilitating the replacing and repairing of locomotive car springs comprising a length of railroad track including 60 spaced rigid rail sections, movable rail sec-

tions interposed between the rigid sections for movement in a vertical plane, U-shaped supporting brackets carried by the inner ends of the rigid track sections receiving the outer ends of the movable track sections, pivot pins 70 connecting the movable track sections to the U-shaped bearing brackets, U-shaped supporting brackets rigidly connected with the inner ends of a pair of the movable track sections receiving the inner ends of the other pair of movable track sections, depending pivot ears carried by the last mentioned brackets, a transversely extending rock shaft mounted in said bearing ears, lift legs keyed to the rock shaft, ground engaging wheels 80 carried by the lift legs, and means for rocking the rock shaft.

In testimony whereof I affix my signature.

CHRISTOPHER CROSSMAN.
